ESTER PRODUCTION

Igor Sobolev, Orinda, Calif., assignor to Shell Oil Company, New York, N.Y., a corporation of Delaware
No Drawing. Continuation-in-part of application Ser. No. 405,858, Oct. 22, 1964. This application Nov. 9, 1967, Ser. No. 681,932

11 Claims. (Cl. 260—486)

ABSTRACT OF THE DISCLOSURE

Reaction of acyclic hydrocarbon monoalkene monocarboxylic acid, epihalohydrin and a reaction-limiting amount of trialkylamine produces 2-hydroxy-3-alkenoyloxypropyltrialkylammonium halide, useful in the production of polymeric wet end additives.

CROSS-REFERENCE TO RELATED APPLICATION

This application is a continuation-in-part of applicant's copending application Ser. No. 405,858, filed Oct. 22, 1964, now abandoned.

BACKGROUND OF THE INVENTION

Compounds incorporating quaternary nitrogen atoms and ester linkages within the molecule are known in the art, being produced, for example, by acylation of ethanolamine derivatives. Such materials have established utility as surface active agents and the like, particularly when the acid moiety of the cationic acid is derived from a long-chain alcanoic acid. In part because of the method of production, it is difficult to prepare esters of this type with additional reactive functional groups, and in general, the cationic esters of the art contain only the ester linkage and the quaternary ammonium moiety as active reaction sites. In the U.S. Patent 3,329,706, issued July 4, 1967, to Sobolev, there is described a process for the production of cationic esters containing a free hydroxyl group and also ethylenic unsaturation. Such esters are characterized as 2-hydroxy-3-alkenoyloxypropyltrialkylammonium halides and are prepared from reaction of the free acid and a glycidyltrialkylammonium halide. Although this process offers a method for the production of such cationic esters in high yield and purity, it does require the pre-formation of the glycidyltrialkylammonium halide. It would be of advantage to provide a method for the production of these cationic esters from simpler and more readily available starting materials.

SUMMARY OF THE INVENTION

It has now been found that an improved process of producing 2-hydroxy-3-alkenoyloxypropyltrialkylammonium halides comprises the process of directly reacting an alkenoic acid, an epoxyhaloalkane and a tertiary amine in an inert polar solvent. In contrast with somewhat related processes of the prior art, the success of the present process is determined by the use of selected reactant ratios, without the use of which little production, or at least a substantially lessened production, of the desired cationic ester is observed.

DESCRIPTION OF PREFERRED EMBODIMENTS

The alkenoic acid employed in the process of the invention is a hydrocarbon carboxylic acid possessing at least one carboxy group and at least one ethylenic link-

2

age, i.e., non-aromatic carbon-carbon double bond, which ethylenic linkage(s) constitutes the only carbon-carbon unsaturation present within the molecule. Preferred acids are acyclic lower monoalkene monocarboxylic acids containing from 3 to 8 carbon atoms, especially those acids wherein the ethylenic linkage is conjugated with the carboxy group. Thus, lower monoalkene monocarboxylic acids such as crotonic acid, 3-butenoic acid, 5-hexenoic acid, 5-methyl-6-heptenoic acid and the like are operable in the process of the invention. Best results are obtained, however, when the ethylenic linkage, in addition to being conjugated with the carboxy group, is also terminal. One class of acids of this type is represented by the formula

wherein a is a whole number from 0 to 5 inclusive. These α -(non- to monoalkyl)acrylic acids are illustrated by acrylic acid, methacrylic acid, ethacrylic acid and α -amylacrylic acid. A particularly preferred class of lower monoalkene monocarboxylic acids, principally because of the desirable properties of the products produced therefrom, comprises acrylic acid and methacrylic acid, generically designated (meth)acrylic acid.

The tertiary amine reactant comprises a trivalent nitrogen atom, each valence of which is satisfied with an alkyl substituent of from 1 to 20 carbon atoms. Such amines are represented by the formula NR_3 wherein each R group independently is alkyl of from 1 to 20 carbon atoms. Preferred tertiary amines have at least two, and more preferably three, lower alkyl substituents, that is, alkyl of from 1 to 4 carbon atoms, and best results are obtained when the nitrogen atom of the tertiary amine possesses at least two methyl substituents. Suitable amine reactants include trimethylamine, triethylamine, tributylamine, dimethyloctylamine, diethyldecylamine, dimethylaurylamine, dimethylstearylamine, dibutyltridecylamine, methylamyldecylamine, triaurylamine and the like.

The epoxyhaloalkane is an m,n -epoxy- o -haloalkane wherein m , n and o represent adjacent atoms in a continuous carbon chain. Although epoxyhaloalkanes of greater chain length are operable, the preferred epoxyhaloalkanes comprise the epihalohydrins, that is, the 2,3-epoxy-1-halopropanes. The halogen moiety of the epihalohydrin reactant is suitably fluorine, chlorine, bromine or iodine, although the preferred epihalohydrins are those wherein the atomic number of the halogen is from 17 to 35, i.e., the middle halogens chlorine and bromine, and particularly preferred as the epoxyhaloalkane reactant is epichlorohydrin.

It has been found that the ratio of reactants present in the reaction mixture exerts a substantial influence upon the conversion of reactants and the yield of the desired 2-hydroxy-3-alkenoyloxypropyltrialkylammonium halide. The stoichiometry of the reaction process would predict the desirability of employing equimolar amounts of each of the three reactants. However, when equimolar amounts of reactants are employed, reduced yields of the desired cationic ester product are obtained. The relative molar amounts of alkenoic acid and epoxyhaloalkane does not appear to be critical, and molar ratios of alkenoic acid to epoxyhaloalkane from about 3:1 to about 1:3 are satisfactorily utilized. Generally, no great excess of either the alkenoic acid or the epoxyhaloalkane is required and no substantial advantage is gained by the use thereof. Molar ratios of alkenoic acid to epoxyhaloalkane that are sub-

stantially stoichiometric, that is, ratios from about 1.5:1 to about 1:1.5 are preferred. It is highly desirable, however, to employ a reaction-limiting amount, i.e., an amount less than the stoichiometric amount, of the trialkylamine reactant in order to obtain the optimum yield of the desired cationic ester product, and the number of moles of trialkylamine per mole of limiting other reactant, that is, mole of alkenoic acid or mole of epoxyhaloalkane, whichever is smaller, should desirably not exceed about 0.95. The use of less than stoichiometric amounts of the amine reactant results, of course, in incomplete conversion of the alkenoic acid and epoxyhaloalkane, but these reactants may be recovered and recycled to improve the overall conversion. Although the selectivity for production of the desired cationic ester not infrequently increases with lessened proportions of the trialkylamine, the use of too small an amount of trialkylamine relative to the other reactants unnecessarily increases the operating expense, because of the required increase in recycle operation, without obtaining any compensating advantage. From practical considerations, the relative amount of trialkylamine should be at least about 0.5 mole per mole of limiting other reactant. Relative amounts of trialkylamine from about 0.5 mole to 0.85 mole, especially amounts from about 0.6 mole to about 0.8 mole, per mole of limiting other reactant are satisfactory.

The process of the invention is conducted in liquid phase solution in an inert polar solvent. Suitable solvents are liquid at reaction temperature and pressure, are capable of dissolving the reactants and are inert to the reactants as well as the products produced therefrom. Illustrative solvents include sulfones such as dimethyl sulfone and sulfolane; N,N-disubstituted lower alkyl amides, e.g., dimethylformamide and N,N-dimethylacetamide; and sulfoxides such as dimethylsulfoxide. Preferred solvents, however, largely for economic reasons, comprise certain alcohols. It has been found that primary alcohols, such as methanol and ethanol, are not inert and are therefore not satisfactory as solvents in the present process, apparently because of a promotion of trans-esterification processes leading to substantially decreased yield of the desired cationic ester. However, when the alcohol possesses at least two non-hydrogen substituents on the carbon to which the hydroxyl group is attached, that is, the alcohol is a secondary or a tertiary alcohol, such trans-esterification processes do not take place extensively and high yields of the desired product are obtained. The preferred alcohol solvents therefore comprise a carbon atom to which is attached one hydroxyl group and from two to three hydrocarbyl substituents which are alkyl of from 1 to 6 carbon atoms or are aryl of 6 carbons, i.e., phenyl, and any unsatisfied valences of the central carbon atom are satisfied by hydrogen substituents. Such alcohols, characterized as di- to trihydrocarbyl carbinols wherein the hydrocarbyl substituents are as defined above, preferably have from 3 to 10 carbon atoms and are illustrated by isopropanol, sec-butanol, tert-butanol, tert-amyl alcohol, triethylcarbinol, dimethyl phenyl carbinol and methyl ethyl phenyl carbinol. More preferred are the di- to trialkyl carbinols wherein the alkyls are alkyl of 1 to 6 carbon atoms and particularly preferred are the di- to trialkyl carbinols having a total of from three to four carbon atoms, i.e., sec-butanol, tert-butanol and isopropanol. The alcohols employed as solvents are preferably substantially anhydrous, as the presence of water appears to be detrimental to the reaction process. The presence of small amounts of water, e.g., up to about 5% of the reaction mixture, may be tolerated without losing the advantages of the invention, but the yield of desired cationic ester will be somewhat lowered.

The method of mixing the reactants and solvent is not critical. Although it is frequently desirable to maintain the concentration of the trialkylamine reactant at a minimum, as by adding the amine in increments to a mixture of the other reactants and solvent, it is also suitable to initially

mix the entire amount of reactants and solvent. The reaction is preferably conducted at somewhat elevated temperatures. Reaction temperatures from about 30° C. to about 125° C. are satisfactory, although reaction temperatures from about 50° C. to about 100° C. are preferred. The process may be conducted at atmospheric, subatmospheric or superatmospheric pressure so long as the reactants are maintained in the liquid phase. Little apparent advantage is gained by the use of reaction pressures considerably different than atmospheric, and the use of substantially atmospheric reaction pressures, e.g., from about 0.5 atmosphere to about 5 atmospheres, is preferred.

It is generally desirable to make some provision in the reaction procedure for the inhibition of alkenoic acid polymerization, particularly when the alkenoic acid is readily polymerizable, e.g., as acrylic acid, methacrylic acid or the like. Surprisingly, it is not necessary to rigorously exclude oxygen from the reaction environment and the process of the invention is conveniently conducted under an atmosphere of air. Prevention of alkenoic acid polymerization is customarily accomplished by the inclusion within the reaction mixture of an inhibitor. Conventional polymerization inhibitors capable of trapping organic free radicals formed during the reaction process are satisfactory, provided that the inhibitor is inert toward the reactants and the products produced therefrom. Preferred inhibitors therefore contain no active hydrogen atoms. Illustrative of suitable inhibitors are the quinones, particularly mono- to dinuclear quinones, e.g., 1,4-benzoquinone, 1,2-benzoquinone, 1,4-naphthoquinone and alkylated or halogenated, particularly chlorinated, derivatives thereof such as chloranil, duroquinone, 2-ethylbenzoquinone and the like; as well as hindered phenols, i.e., phenols wherein the phenolic hydroxyl group is hindered by the presence of branched alkyl substituents on each ring position ortho relative to the hydroxyl group. Illustrative of the class of hindered phenolic inhibitors are 2,6-di-tert-butylphenol, 2,6-di-tert-butyl-4-methylphenol, 2,6-diisopropylphenol and 2,4,6-tri-tertbutylphenol. The inhibitor, if employed, is added in comparably small amounts. Amounts of inhibitor from about 0.001 to about 5 molar percent based on the alkenoic acid reactant are suitable, while amounts from about 0.01 to about 3 molar percent on the same basis are preferred.

Subsequent to reaction the product is separated and recovered by conventional methods such as precipitation through the addition of a non-solvent, crystallization through a cooling procedure, by selective extraction or the like.

The products of the invention are 2-hydroxy-3-alkenoyloxypropyltrialkylammonium halides. Illustrative of such products are 2-hydroxy-3-acrylyloxypropyltrimethylammonium chloride; 2-hydroxy-3-methacrylyloxypropyltrimethylammonium chloride, 2-hydroxy-3-ethacrylyloxypropyltrilaurylammmonium bromide, 2-hydroxy-3-methacrylyloxypropylmethyl dibutylammonium chloride and 2-hydroxy-3-(2-ethylacrylyloxy)propyldimethylstearylammmonium chloride.

The products of the invention are suitable for use in numerous applications. As cationic materials they exhibit surface activity and are further useful as biocidal chemicals, particularly germicides. The number and variety of reactive functional groups present allow wide usage as chemical intermediates, wherein, for example, the hydroxyl group may be esterified or etherified, other useful quaternary ammonium salts prepared by anion exchange, or alternatively the unsaturated linkage can be epoxidized to form useful epoxy resin precursors. A particularly important utility for the products of the invention is in the formation of polymeric materials, useful, for example, as wet end additives in paper manufacture.

To further illustrate the improved process of the invention, the following examples are provided. It should be understood that the details thereof are not to be regarded as limitations, as they may be varied as will be understood by one skilled in this art.

Example I

A solution was prepared from 200 g. tert-butyl alcohol, 60 g. (0.80 mole) methacrylic acid, and 4 g. 2, 6-di-tert-butyl-4-methylphenol inhibitor. The solution was maintained at approximately 10° C. while gaseous trimethylamine was bubbled into the solution until the solution weight had increased 38 g. (which represents 0.64 mole of the amine). To the mixture was added 74 g. (0.80 mole) of epichlorohydrin. A 180-200 ml. aliquot of this solution was placed in a separate container and shaken for 72 hours while maintained at 55° C. To the product mixture, which contained appreciable quantities of crystalline precipitate when cooled to room temperature, was added six times its weight of acetone and the product mixture was allowed to stand for one hour. Filtration afforded crystals which were washed with acetone and dried under vacuum at 30-40° C. The yield of 2-hydroxy-3-methacryloyloxypropyltrimethylammonium chloride was 66% based upon the trimethylamine charged.

Example II

By procedures similar to that of Example I, trimethylamine, epichlorohydrin and methacrylic acid were reacted, employing a variety of solvents. The results are shown in Table I wherein the yield represents yield of 2-hydroxy-3-methacryloyloxypropyltrimethylammonium chloride based on the trimethylamine charged.

TABLE I

	Solvent			
	Dimethylsulfoxide	Sulfolane	Ethanol	Tert-butyl Alcohol
Trimethylamine, moles/100 g. solution	0.121	0.175	0.193	0.179
Methacrylic acid, moles/mole amine	1.21	1.18	1.11	1.24
Epichlorohydrin, moles/mole amine	1.21	1.18	2.01	1.24
Temperature, ° C.	50	55	50	60; 76
Time, hours	72	48	16	5; 24
Conversion of trimethylamine	90	67	100	91±3
Yield, percent	80	52	0	71

Example III

By a procedure similar to that of Example I a series of reactions employing varying molar ratios of epichlorohydrin, trimethylamine and methacrylic acid was conducted. The results are shown in Table II, wherein the yield represents yield of 2-hydroxy-3-methacryloyloxypropyltrimethylammonium chloride based on the amine charged. The solvent in all cases was tert-butyl alcohol, and each reaction mixture was heated at 60° C. for 48 hours with the exception of Experiment 4 wherein the reaction mixture was heated at 60° C. for 6 hours and then at 75° C. for 24 hours.

TABLE II

Experiment	1	2	3	4
Trimethylamine, moles/100 g. solution	0.179	0.168	0.206	0.186
Methacrylic acid, moles/mole amine	1.04	1.15	1.03	1.28
Epichlorohydrin, moles/mole amine	0.99	1.35	0.95	1.28
Conversion of trimethylamine	77	100	55	85
Yield, percent	46	83	24	79

It is observed from comparison of Experiments 1 and 3, wherein substantially stoichiometric quantities of reactants were employed, with Experiments 2 and 4, wherein a limiting amount of the amine was employed, that utilization of the non-stoichiometric quantities results in substantially higher yields of the desired cationic ester product.

Example IV

When dimethylallylamine is reacted with acrylic acid and epibromohydrin in isopropanol solution, the molar ratio of reactants being 0.7:1:1, a good yield of 2-hydroxy-3-acryloyloxypropyltrimethylammonium bromide is obtained.

Example V

When the procedure of Example I is repeated, except that an equivalent amount of crotonic acid is employed in place of the methacrylic acid, a good yield of 2-hydroxy-3-crotonyloxypropyltrimethylammonium chloride is obtained.

Example VI

Several experiments were conducted by procedures similar to that of Example I, except that other alcohol solvents were employed and the 2-hydroxy-3-methacryloyloxypropyltrimethylammonium chloride was obtained by cooling the product mixture at -18° C. for 24 hours before filtration. The reaction mixture had been maintained at 60° C. for 48 hours. The results are shown in Table III.

TABLE III

Solvent	Isopropyl alcohol	Sec-butyl alcohol
Trimethylamine, moles/100 g. solution	0.166	0.166
Methacrylic acid, moles/mole amine	1.28	1.28
Epichlorohydrin, moles/mole amine	1.25	1.25
Conversion of trimethylamine	75	93
Yield, percent	50	80

I claim as my invention:

1. The process of producing 2-hydroxy-3-alkenoyloxypropyltrimethylammonium halide by intimately contacting (a) acyclic hydrocarbon monoalkene monocarboxylic acid of from 3 to 8 carbon atoms; (b) epihalohydrin wherein the halogen is halogen of atomic number from 17 to 35, the molar ratio of epihalohydrin to said monocarboxylic acid being from about 3:1 to about 1:3, and (c) an amount greater than about 0.5 mole per mole of limiting other reactant but less than stoichiometric of trialkylamine wherein each alkyl independently is alkyl of from 1 to 20 carbon atoms; in liquid-phase solution in inert polar solvent, at a temperature from about 30° C. to about 125° C.
2. The process of claim 1 wherein the monocarboxylic acid is α -(non- to mono-alkyl)acrylic acid wherein any alkyl is alkyl of from 1 to 5 carbon atoms, and said inert polar solvent is di- to trihydrocarbyl carbinol of 3 to 10 carbon atoms.
3. The process of claim 2 wherein the epihalohydrin is epichlorohydrin.
4. The process of claim 3 wherein the amine is dimethylalkylamine wherein the alkyl is alkyl of from 1 to 20 carbon atoms present in an amount from about 0.5 mole or about 0.95 mole per mole of limiting other reactant, and the di- to trihydrocarbyl carbinol is di- to trialkyl carbinol.
5. The process of claim 4 wherein the amine is trimethylamine.
6. The process of claim 4 wherein the monocarboxylic acid is acrylic acid or methacrylic acid, the di- to trialkyl carbinol is a di- to trialkyl carbinol of from 3 to 4 carbon atoms, and said contacting is conducted in the presence of from about 0.001 to about 5 molar percent based on said monocarboxylic acid of a polymerization inhibitor having no active hydrogen atoms and at a temperature from about 50° C to about 100° C.

7. The process of claim 6 wherein the amine is trimethylamine.

8. The process of claim 7 wherein the acid is methacrylic acid and the molar ratio of epichlorohydrin to said methacrylic acid is from about 1.5:1 to about 1:1.5.

9. The process of claim 8 wherein the carbinol is sec-butyl alcohol.

10. The process of claim 8 wherein the carbinol is isopropyl alcohol.

11. The process of claim 6 wherein the acid is acrylic acid.
